UNITED STATES PATENT OFFICE.

FRANCIS M. MYERS, OF WINDSOR, MISSOURI, ASSIGNOR OF ONE-THIRD TO CHARLES A. DRAPER, OF WINDSOR, MISSOURI, AND ONE-THIRD TO PHILIP H. KILPATRICK, OF CORINTH, MISSISSIPPI.

RAILWAY SIGNAL SYSTEM.

No. 845,188.

Specification of Letters Patent.

Patented Feb. 26, 1907.

Application filed March 22, 1906. Serial No. 307,412.

To all whom it may concern:

Be it known that I, FRANCIS M. MYERS, a citizen of the United States, residing at Windsor, Henry county, State of Missouri, have invented certain new and useful Improvements in Railway Signal Systems, of which the following is a specification.

This invention relates to railway-signals; and its object is to give, and if necessary repeat, a visible or other signal in the cab of a locomotive or on any other part of a train to warn the engineer or other attendant of approaching danger either in the form of another train, a broken rail, an open switch or bridge, or other obstruction.

The invention also embodies an improved arrangement of circuits and various features of advantage which will be pointed out more in detail hereinafter.

In the drawings, Figure 1 represents diagrammatically the arrangements of circuits included in one embodiment of my invention as applied to one track of a double-track road and the indicating mechanism employed. Fig. 2 shows a switch wired in conformity with my invention. Fig. 3 is a detail plan of a preferred form of contact-shoe, and Fig. 4 shows the arrangements of circuits on a single-track road.

In all of the figures like characters designate like parts.

Referring to Fig. 1, 1 designates one of the tracks of a double-track road on which trains move in the direction of the arrow. 2 is one of the rails of said track and is insulated and continuous, and 3 is the other rail, which is insulated and divided into sections forming a series of blocks, (indicated in Fig. 1 by the characters 4, 5, and 6.) Arranged in each block and adapted to make contact with a properly-arranged shoe on a passing locomotive is a series of contact-rails 7, in the drawings three of said rails being shown—one near each end of a block and one at the center thereof. The contact-rails of each block are electrically connected with the rail 3 of the adjoining or any other preferred block by the line-wire 8, and each rail 3 is electrically connected with the continuous rail 2 through a track-battery 9.

Upon the locomotive using my system will be arranged the indicating mechanism and operating-circuits now to be described, and it

may here be stated that although this specification describes my system as applied to a locomotive, yet my invention is not limited to that particular style of conveyance, but may be applied equally as well to any other vehicle moving upon a railroad or other track.

10 is a battery or generator from which run the positive and negative wires 11 and 12, respectively, through a magnet 13, shown in the form of a solenoid, resistance 14, and switch 15, thus completing the circuit and energizing the magnet 13.

Arranged in operative relation with the magnet 13 is an indicating mechanism comprising a semaphore 16 and a dial 17. Any other approved indicating devices may be operatively connected with the magnet without departing from the spirit of my invention. Also additional signals, audible or visible, may be added by suitably connecting their operating mechanism with the moving part of the magnet; but the mechanism about to be described is the preferred form.

The semaphore 16 is pivoted at 18 and is held in set position by the magnet 13 and through suitable levers 19 is adapted to operate the rotatable dial 17. Obviously the dial may be operated directly by the solenoid and the semaphore dispensed with or other devices substituted therefor. The dial 17 is provided with a series of numerals or other symbols 20, indicating the respective positions of the contact-rails 7, hereinbefore referred to. The hub of the dial is formed with teeth 22, one for each numeral 20, which adapts the dial to be rotated one step to each complete oscillation of the semaphore.

It will now be understood that when the circuit from battery 10 is broken (as by contact-rail 7) the magnet 13 will be deenergized and the semaphore will drop to the danger position, as shown in dotted lines, and simultaneously the dial will be rotated one step, in the present instance from "3" to "1," indicating that the locomotive has just passed the first contact-rail of the block. If the semaphore be restored to its set position, the operation will be repeated, when the circuit is again broken, and the dial will indicate that the second contact-rail has been passed.

For the purposes of this invention the power of the magnet 13 is so adjusted as to

be capable of holding the semaphore in set position, as shown in full lines in Fig. 1, as long as the circuit is closed; but it is incapable of restoring the same while the resistance 14 is in circuit. However, the semaphore may be restored to set position by shunting the current around said resistance, and for this purpose there is provided the shunts 23 and 24, respectively, the former of which is closed 10 by the push-button 25, normally held in open position, and the latter by the switch 26, also normally held in open position and adapted to be closed by the action of a relay-magnet 27. The wires 28 and 29 from the 15 relay-magnet are respectively electrically connected with one of the locomotive-wheels 37, having contact with the continuous rail 2, and a contact-shoe 30, which shoe is adapted to make electrical contact with contact-rails 20 7. This contact-shoe 30 is arranged on the locomotive slightly in the rear of the circuit-breaker 31, operating the switch 15.

The circuit-breaker 31 is shown in detail in Fig. 3, and its construction is well adapted to the uses of this system. The brush 32, of spring form, is mounted at both ends in sliding boxes 33, secured to bars 34 and held thereon by stops 35. A link 36, of insulating material, pivotally connects the 30 brush with the spring-switch 15. Thus when the brush strikes the contact-rail 7 in the position shown in Fig. 3 it is raised, as shown in dotted lines, one of its ends sliding on the bar 34, and through the link 36 it 35 operates to open the switch 15, and immediately upon passing said contact-rail the switch is restored.

The contact-shoe 30 is similar in construction to the circuit-breaker 31, except 40 that the link 36 is omitted and the wire 29 is electrically connected to the brush.

The operation of the system as thus far described may be stated as follows: Supposing a locomotive is just entering block 5 from 45 left to right and that the track ahead is clear, the dial 17 will show the numeral "3," indicating that the third (and in the present case the last) contact-rail of the block just left has been passed, and the semaphore 16 50 will be set at "safety." As the circuit-breaker 31 strikes the first contact-rail 7 of the block 5 the circuit of battery 10 will be interrupted and the magnet 13 consequently deenergized, resulting in semaphore 16 dropping to "danger" and simultaneously 55 rotating the dial 17 one step, exposing the numeral "1," indicating that the first contact-rail of the block has been passed. As the circuit-breaker slides off of the rail 7 the 60 switch 15 restores the circuit of battery 10; but the resistance 14 prevents the semaphore being restored, and the danger-signal continues in full view of the engineer, or if an audible signal is connected with the magnet, as hereinbefore suggested, it continues to 65

sound until the resistance is cut out of circuit. As the circuit-breaker 31 leaves the contact-rail the shoe 30 makes electrical contact therewith, and a circuit is formed from track-battery 9 of block 6 through 70 rail 2, wheel 37 of the locomotive, wire 28, relay-magnet 27, wire 29, shoe 30, contact-rail 7, line-wire 8, and rail 3 of block 6, thus energizing relay-magnet 27, which operates to momentarily close the switch 26 and shunt 75 the current from battery 10 around the resistance, and thus restore the semaphore to "safety." The foregoing operation will be repeated at the second and third contact-rails of the block, the dial 17 being rotated 80 one step at each operation, thus indicating the relative position of the locomotive. Again, supposing that the locomotive is just entering block 5, but that there is a train or other obstruction in block 6, the operation of 85 breaking and restoring the circuit of battery 10 will be the same as before described; but the relay-magnet 27 will not act to shunt the current around the resistance, owing to the fact that the track-battery 9 of block 6 will 90 be short-circuited through the wheels of the obstructing train. Hence the danger-signal will continue to warn the engineer until he restores it to "safety" by pressing the push-button 25 in the shunt 23, and if the obstruction is still present in block 6 when the locomotive reaches the second contact-rail 7 the danger-signal will be repeated, and likewise with the remaining contact-rails in that block. 95

From the above-described operation it will be observed that should either rail of block 6 be broken or should they be electrically connected by any obstruction whatsoever, so that track-battery 9 is short-circuited, the engineer of a train approaching 105 through block 5 would be thrice warned of the danger by the failure of the relay-magnet 27 to become energized, and thus act to restore the danger-signal to the position of safety. 110

Referring to Fig. 2, it will be observed that the rail 2, which is necessarily broken for the purposes of the switch, is electrically connected, as at 38, and that the rail 3 is electrically connected, as at 39, with the rail 40 of the switch. Arranged on the movable part 41 of the switch is the contact-point 42, adapted to make electrical contact with the rail 2 when the switch is open, thus short-circuiting the track-battery 9 through rail 3, rail 40, part 41, contact-point 42, and rail 2, and consequently giving the danger-signal to an approaching locomotive. Many other arrangements of switch-wiring may be resorted to without departing from my invention, the object being to either short-circuit the track-battery 9 or to break the continuity of the relay-circuit-making members of the track-battery, any one of which will operate to give 125 130

the danger-signal to an approaching locomotive. Suitable wirings may also be arranged at draw-bridges and other temporary obstructions whereby the relay-circuit-making members are disarranged when the track is not clear.

Referring to Fig. 4, it will be seen how a single-track road on which trains move in either direction may be wired to warn moving trains of the proximity of each other or of other obstacles.

What I claim is—

1. In a block-signal system, contact-rails arranged at a plurality of points in each block, electromechanical indicating means carried by a locomotive for giving thereon a danger-signal and for visibly indicating thereon the position of said locomotive with relation to said contact-rails, and means for operating said indicating means as each point is reached by said locomotive.

2. The combination of a complete electric circuit arranged upon a locomotive and adapted to be broken by a track contact-rail, indicating mechanism controlled by said circuit and adapted to be operated by the breaking thereof, a resistance in said circuit adapted to prevent the resetting of said mechanism, and a relay adapted to receive energy from a track-battery and operating to form a shunt-circuit on the locomotive around said resistance, whereby said mechanism is reset.

3. The combination of a complete electric circuit arranged upon a locomotive and adapted to be broken by a track contact-rail, indicating mechanism controlled by said circuit and adapted to be operated by the breaking thereof, a resistance in said circuit adapted to prevent the resetting of said mechanism, and means including a track battery and circuit for closing a shunt-circuit on the locomotive around said resistance, whereby said mechanism is reset.

4. The combination of a complete electric circuit in which is included a solenoid, a resistance-coil, and a normally closed spring-switch, said switch being provided with a circuit-breaker, a shunt around said resistance coil, said shunt having a switch normally held in open position, an indicator adapted to be held in set position by said solenoid when said coil is in circuit and adapted to be raised to set position by said solenoid only when the current is shunted around said coil, all of said elements being arranged upon a moving locomotive, and a stationary contact-rail arranged to act upon said circuit-breaker.

5. The combination with a track comprising a continuous insulated rail and a sectional insulated rail, contact-rails arranged contiguous to said track at intervals in each of the sections, line-wires electrically connecting the contact-rails of each section with the sectional rail of another section, and an elec-

tric battery arranged between each sectional rail and the continuous rail, of a locomotive adapted to run on said track and provided with shoes adapted to touch said contact-rails in passing, said shoes causing the operation of indicating mechanism carried on said locomotive whereby the position of said locomotive relative to the sections may be determined.

6. The combination with a closed electric circuit in which is included a magnet and a resistance, a shunt around the resistance provided with a switch normally held open, an indicator adapted to be held in set position by said magnet with the resistance in circuit but to be attracted to its set position only when the current is shunted around the resistance, whereby when the circuit is momentarily broken and restored the indicator will move from set position and will not be reset until the shunt-switch is closed, all of the foregoing elements being carried on a locomotive, of means arranged contiguous to the locomotive-track for momentarily breaking said circuit.

7. The combination with a closed electric circuit in which is included a magnet, a resistance and a spring-switch, said switch being normally closed, a shunt around the resistance, said shunt being provided with a switch normally held open, an indicator adapted to be held in set position by said magnet with the resistance in circuit but to be attracted to set position only when the current is shunted around the resistance, all of the foregoing elements being carried on a locomotive, of means arranged contiguous to the locomotive-track for momentarily operating said switch.

8. The combination of a closed electric circuit in which is included a magnet, a resistance, and a normally closed spring-switch, a normally open shunt around said resistance, a relay-magnet adapted, when energized, to close said shunt, and an indicator controlled by said first-mentioned magnet, all of the above elements being carried on a locomotive, with a contact-rail adapted to break said closed circuit momentarily, and a track-battery arranged to momentarily energize said relay-magnet after said closed circuit has been broken and restored.

9. The combination of a locomotive carrying a battery and a complete electric circuit connected therewith, a resistance and a normally closed spring-switch in said circuit, said switch being provided with a circuit-breaker adapted to be operated by a contact-rail, an indicating mechanism controlled by the breaking and restoring of said circuit, a normally open shunt around said resistance, and a relay-magnet adapted, when energized, to close said shunt, the winding of said relay having connection respectively with a wheel of said locomotive and a contact-shoe adapt-

ed to coöperate with a contact-rail, with a railway-track upon which said locomotive is adapted to run, one rail of said track being insulated from the ground and continuous, and the other being divided into insulated sections forming blocks, a track-battery arranged between and connected with each sectional rail and the continuous rail, and a contact-rail for each block arranged to coöperate with said circuit-breaker and contact-shoe and having connection with the sectional rail of another block.

10. The combination of a locomotive carrying a battery and a complete electric circuit connected therewith, a resistance and a normally closed spring-switch in said circuit, said switch being provided with a circuit-breaker adapted to be operated by a contact-rail, an indicating mechanism controlled by the breaking and restoring of said circuit, a normally open shunt around said resistance, and a relay-magnet adapted, when energized, to close said shunt, the winding of said relay having connection respectively with a wheel of said locomotive and a contact-shoe adapted to coöperate with a contact-rail, with a railway-track upon which said locomotive is adapted to run, one rail of said track being insulated from the ground and continuous, and the other being divided into insulated sections forming blocks, a track-battery arranged between and connected with each sectional rail and the continuous rail, and a series of contact-rails for each block arranged to coöperate with said circuit-breaker and contact-shoe and having connection with the sectional rail of another block.

11. The combination of a locomotive carrying an electric generator and a complete circuit including therein a resistance, a magnet, and a normally closed spring-switch, said switch being provided with a circuit-breaker adapted to be operated by a contact-rail, an indicator comprising a semaphore and a dial provided with numerals or other symbols, said indicator being adapted to be held in set position by said magnet with the resistance in circuit but to be attracted to set position only when the current is shunted around said resistance, a normally open shunt around said resistance, a relay-magnet having terminals respectively in a wheel of the locomotive and in a contact-shoe, said magnet being adapted, when energized, to close said shunt, and said shoe being arranged in the rear of said circuit-breaker and adapted to touch a contact-rail, a track comprising a continuous insulated rail adapted to have contact with said wheel and a sectional insulated rail forming blocks, an electric generator between and connected to each sectional rail and the continuous rail, contact-rails arranged at a plurality of points in each block and adapted to coöperate with said circuit-breaker and contact-shoe successively, said points corresponding in number or location to the numerals or symbols of said dial, and a line-wire connecting the contact-rails of each block with the sectional rail of another block.

12. The combination of a locomotive carrying an electric generator and a complete circuit including therein a resistance, a magnet and a normally closed spring-switch, said switch being provided with a circuit-breaker adapted to be operated by a contact-rail, an indicator comprising a semaphore and a dial provided with numerals or other symbols, said indicator being adapted to be held in set position by said magnet with the resistance in circuit, but to be attracted to set position only when the current is shunted around said resistance, a normally open shunt around said resistance, another normally open shunt around said resistance, a relay-magnet having terminals respectively in a wheel of the locomotive and in a contact-shoe, said magnet being adapted, when energized, to close said first-mentioned shunt, and said shoe being arranged in the rear of said contact-shoe and adapted to touch a contact-rail, a track comprising a continuous insulated rail adapted to have contact with said wheel and a sectional insulated rail forming blocks, an electric generator between and connected to each sectional rail and the continuous rail, contact-rails arranged at a plurality of points in each block and adapted to coöperate with said circuit-breaker and contact-shoe successively, said points corresponding in number or location to the numerals or symbols of said dial, and a line-wire connecting the contact-rails of each block with the sectional rail of another block.

13. The combination with a complete electric circuit arranged upon a locomotive and adapted to be broken by a track-contact rail, indicating mechanism controlled by said circuit and adapted to be operated by the breaking thereof, a resistance in said circuit adapted to prevent the resetting of said mechanism, and a relay-magnet adapted, when energized, to close a shunt around said resistance whereby said mechanism may be reset, of a railway-switch, a track-battery, wirings so arranged therewith that the circuit of said battery is closed when the switch is open and vice versa, and means for electrically connecting the windings of said relay-magnet with said wirings at a predetermined position in the travel of said locomotive.

14. The combination with a complete electric circuit adapted to operate an indicating mechanism by the breaking of said circuit and to reset said mechanism by the remaking of said circuit and the closing of a shunt around a resistance, a relay-magnet adapted, when energized, to close said shunt, a nor-

5 mally closed spring-switch in said circuit, all of said elements being arranged upon a moving locomotive, of a railway-switch, a track-battery, wirings so arranged with said battery and railway-switch that the circuit is closed when the switch is open and vice versa, a contact-rail adapted to momentarily open said spring-switch, and means for momentarily connecting the winding of said relay-magnet with said wirings immediately following the actuation of said spring-switch.

15. The combination with an electric signal system, of a circuit-breaker comprising a spring-brush having its ends mounted in sliding boxes, and a link adapted to operate the switch.

20 16. The combination with an electric signal system, of a circuit-breaker comprising a spring-brush mounted in sliding boxes, said boxes having a limited longitudinal movement, and means on said brush adapted to operate a switch.

25 17. The combination with an electric signal system, of a circuit-breaker comprising a brush mounted in sliding boxes, said boxes having a limited longitudinal movement, and insulated means on said brush connecting it with the movable part of a switch.

30 18. The combination with an electric-rail-way system, of a contact-shoe comprising a spring-metal brush mounted in sliding boxes, said boxes having a limited longitudinal movement.

35 19. A contact-shoe comprising a brush formed of spring-metal, said brush being pivoted at its ends to sliding boxes, guiding means for said boxes, and stops to limit their movement.

40 20. A contact-shoe comprising a brush formed of spring-metal, sliding boxes on the ends of said brush, and stops to limit the travel of said boxes.

45 21. In a block-signal system, an indicator carried on the locomotive, a contact-rail arranged in each block, means actuated by said rail for operating said indicator regardless of the condition of the track-circuits, and means for returning said indicator to its first position when the track-circuits are in 50 normal condition only.

55 22. In a block-signal system, an indicator carried on the locomotive, a contact-rail arranged in each block, means actuated by said rail for operating said indicator regardless of the condition of the track-circuits, and means for subsequently actuating said operating means when the track-circuits are in normal condition only.

60 23. In a block-signal system, an indicator carried on the locomotive, operating means for said indicator, means for actuating said operating means regardless of the condition of the track-circuits, and means for subsequently actuating said operating means

when said track-circuits are in normal condition only. 65

24. In a block-signal system, an indicator carried on the locomotive, operating means for said indicator, means for actuating said operating means regardless of the condition of the track-circuits, whereby said indicator will show "danger," and means for immediately thereafter actuating said operating means when the track-circuits are in normal condition only, whereby said indicator will be returned to its first position if the track-circuits are undisturbed. 70

15 25. In a railway-signal system, a combined indicator carried on the locomotive for denoting both the track condition and the position of said locomotive with relation to predetermined points along the track, and means for operating said indicator. 80

20 26. A contact-shoe comprising a brush formed of spring-metal, sliding boxes attached to and housing the ends of said brush and stops to limit the travel of said boxes. 85

25 27. In a block-signal system, an indicator carried on the locomotive for denoting both the track condition and the relative position of the locomotive, means for operating said indicator at a point along the track, and means for immediately thereafter resetting said indicator when the track-circuits are in normal condition only. 90

30 28. In a block-signal system, an indicator carried on the locomotive, said indicator comprising a danger-signal and a dial having figures or other symbols corresponding with points along the track, a magnet adapted, when energized, to hold said signal to "safety," a source of electricity and a circuit adapted to energize said magnet, and means for breaking and making said circuit as each point is passed by the locomotive. 105

35 29. In a block-signal system, an indicator carried on the locomotive, said indicator comprising a danger-signal and a dial having figures or other symbols corresponding with points along the track, a magnet adapted when partly energized to hold said signal to safety and when fully energized to raise said signal to "safety" and said signal adapted to drop to "danger" when said magnet is de-energized, and to move said dial one point, a source of electricity and a circuit adapted to energize said magnet, means for breaking said circuit as each point is reached by the locomotive, and means depending upon the condition of the track-circuits for partially or wholly restoring said first-mentioned circuit immediately following the breaking thereof. 110

In testimony whereof I affix my signature in presence of two witnesses.
